UNITED STATES PATENT OFFICE

ROBERT WILHELM VOIGT, OF DRESDEN, GERMANY, ASSIGNOR TO THE FIRM JOHANN
CARL MÜLLER, OF DRESDEN, GERMANY

MACHINE FOR PACKING CIGARETTES

Application filed March 24, 1928, Serial No. 264,497, and in Germany May 11, 1927.

This invention relates to machines for packing cigarettes or the like. In the machine described in the specification of my prior application for patent, Serial No. 5 195,419, U. S. Patent No. 1,706,716 there are provided the star shaped cover plates 30 and the several feed bands for the cigarettes each of which is adapted to feed the cigarettes from one station to a transversely 10 extending feed track 36. The cigarettes fed to the track 36 transversely thereof are fed along this feed track by pushers in successive groups and then transferred to the slides of the containers. The pushers which 15 engage the cigarettes from above are secured to a belt or the like provided above the track and moved forwards in the longitudinal direction of the track, the horizontal feed planes which are parallel to one another being stepped by the thickness of 20 a cigarette, and the transverse feed track bridging the space between the separate feeding means in such manner that the cigarettes pushed from the first feed band by 25 the pushers pass onto the bridge level therewith, beyond which the next feed band is located at a level which is lower by the thickness of a cigarette and so on. The pushers of course must be lowered correspondingly so that they can act on the lower 30 layer from above. According to my said prior specification this result is obtained by providing the bridges with suitable passages for the pushers at the steps, the bridges terminating just short of the next transverse 35 feed band. As a result, just at the point where the cigarettes are transferred from the bridge to the next layer there is no support for the cigarettes and I find from 40 experience that the absence of such support leads to displacement and incorrect feeding of the cigarettes.

As distinguished therefrom the parts (bridges) located between the separate feed 45 devices for the feed band are provided with longitudinal slots through which the tines of the rake-like pushers may pass when the pushers are lowered.

Now the layers which are to be transferred to the slides of the containers as is

well known are not alike as regards the number of cigarettes therein since for example one layer consists only of twelve, and another thirteen cigarettes if twenty five cigarettes are to be introduced into a slide, so that the width occupied by the groups to be fed forwards by the pusher differs. This circumstance must be taken account of by correspondingly dimensioning the pusher. In feeding forwards the narrower cigarette 55 layer its width must be adjusted to the width of the feed track and in feeding the wider layer containing more cigarettes its width must be correspondingly increased. This 60 result is attained in accordance with the invention by forming a side or sides of the rake-like pusher as a hingedly mounted part or parts adapted to be moved by means of a spring or the like into operative position, this part in the forward movement of the 65 pusher being first moved by controlling means into a position reducing the width of the pusher by the amount of this movable part until the controlling means move the 70 movable part back into position to increase 75 the width of the pusher.

The invention is illustrated in the accompanying drawings in which Fig. 1 is a side elevation showing those parts of the machine necessary for an understanding of the 80 invention. Fig. 2 is a front elevation while Figs. 3 and 4 show details. Fig. 5 is a partial top plan view of the parts of the machine necessary for the understanding of 85 my invention. Fig. 6 shows in enlarged detail the cooperative action of bridge members 3 and tines 4' of the pusher 4.

In Fig. 1 there are shown two feed bands 1, 2, for the cigarettes consisting of endless belts. The band 2 is stepped from the band 90 1 by the thickness of a cigarette. Between the two feed bands is provided a fixed bridge 3 level with the band 1.

The cigarettes fed to the band 1 and collected into a group are fed by the pusher 95 4 over the bridge 3 on to the cigarettes which have been fed by the band 2 and collected into a group. The pusher 4 is formed as a rake with tines 4'. The rake 4 is mounted on an angle bracket 5 secured 100

to the lower ends of two vertical guide rods 6. These guide rods are longitudinally movable in bosses 7 in a cross bar 8 on the downturned ends 9 of which are mounted guide rollers 10 which run in horizontal guide slots 11 of fixed guide rails 12.

The rods 6 are connected to one another at their upper ends by a cross bar 13 and are secured thereto by means of nuts 14. The cross bar carries at each of its ends a roller 15. The rollers 15 run along the upper edges of guide rails 16, which first extend parallel to one another and then incline at 17. Between the cross bar 8 and the angle bracket 5 on the rods 6 are mounted coil springs 18 which tend to press the bracket 5 with the rakes 4 downwardly. As soon as the rollers 15 can slide downwards on the inclined surfaces 17 the previously compressed springs 18 extend and the rakes 4 are moved downwards. Their tines 4' enter longitudinal slots in the bridge member 3 and the rake 4 moves into the lower position shown in dotted lines in Figure 1. In this lower position it moves into contact with the layer of cigarettes on the feed band 2.

On the pusher 4 is secured by means of an angle bracket 19 a brush 20 or the like which, on the pusher 4 being lowered into the position shown in dotted lines, bears on the layer of cigarettes fed by the feed band 1 and holds and secures these cigarettes in the correct position while they are being transferred on to the cigarettes on the band 2.

In order to adjust the rake-like pusher to the width of the different layers of cigarettes there is provided at one side an extension 22 rotatable about the hinge pin 21 and also formed with tines 4'. Figures 3 and 4 show this extension 22 in two different positions in plan. As shown in these figures a projection 23 is provided on the end of the pusher 4 against which the extension 22 is adapted to be pressed by the blade spring 24 which bears on the extension 22 and is secured by screws to the rake tines 4'. The extension 22 carries at its end a roller 25 which is freely rotatable about a vertical axis 26. This roller moves on a guide rail 27 shown in dotted lines in Fig. 3. As long as the roller travels in the manner shown in Fig. 4 on the straight part of the guide rail 27 the extension 22 is so held against the pressure of the spring 24 that the rake-like pusher 4 is only of a width corresponding to that of the first layer of cigarettes which is fed by the feed band 1. As soon however as the roller 25, on further movement of the pusher in the direction of the arrow indicated in Figs. 3 and 4, passes onto the inclined surface 27' of the guide rail 27 the extension 22 under the action of the spring 24 moves into operative position i. e.

moves into the position shown in Figure 3.

In this position the rake-like pusher 4 is extended laterally in such manner that it also engages the wider layer of cigarettes fed by the endless feed band 2 and feeds such layer forwards.

I claim:

1. In a machine for packing cigarettes into a packet in combination with a feed track of the cigarettes, spaced feed bands disposed transversely of said feed track and adapted to feed groups of cigarettes to said track, said spaced feed bands stepped from one another by the thickness of a cigarette, a pusher movable in the longitudinal direction of the feed track and adapted to feed the groups of cigarettes to the packet, said pusher formed with tines to engage the cigarettes, a bridge member bridging the space between the spaced feed bands, said bridge member formed with slots to allow the passage of the tines of the pusher, and means for lowering the pusher adjacent the bridge member, whereby it will engage with the next group of cigarettes.

2. In a machine for packing cigarettes into a packet in combination with a feed track for the cigarettes, spaced feed bands disposed transversely of said feed track and adapted to feed groups of cigarettes to said track, said spaced feed bands stepped from one another by the thickness of a cigarette, a pusher movable in the longitudinal direction of the feed track and adapted to feed the groups of cigarettes to the packet, said pusher formed with tines to engage the cigarettes, a bridge member bridging the space between the spaced feed bands, said bridge member formed with slots to allow the passage of the tines of the pusher, means for lowering the pusher adjacent the bridge member, whereby it will engage with the next group of cigarettes and means associated with the pusher to hold the cigarettes as they are transferred from one feed band to the next.

3. In a machine for packing cigarettes into a packet in combination with a feed track for the cigarettes, spaced feed bands disposed transversely of said feed track and adapted to feed groups of cigarettes to said track, said spaced feed bands stepped from one another by the thickness of a cigarette, a pusher movable in the longitudinal direction of the feed track and adapted to feed the groups of cigarettes to the packet, said pusher formed with tines to engage the cigarettes, said pusher also formed with a lateral extension, said extension movable into and out of operative position, a bridge member bridging the space between the spaced feed bands, said bridge member formed with slots to allow the passage of the tines of the pusher, and means for lowering the pusher adjacent the bridge mem-

ber, whereby it will engage with the next group of cigarettes.

4. In a machine for packing cigarettes into a packet in combination with a feed track for the cigarettes, spaced feed bands disposed transversely of said feed track and adapted to feed groups of cigarettes to said track, said spaced feed bands stepped from one another by the thickness of a cigarette, 10 a pusher movable in the longitudinal direction of the feed track and adapted to feed the groups of cigarettes to the packet, said pusher formed with tines to engage the cigarettes, said pusher formed with a lateral extension and means for moving said extension into and out of operative position said means including a roller carried by said extension, a cam bar disposed in the path of said roller and a spring serving to press said roller 15 against said cam bar, a bridge member bridging the space between the spaced feed bands, said bridge member formed with slots to allow the passage of the tines of the pusher, and means for lowering the pusher 20 adjacent the bridge member, whereby it will engage with the next group of cigarettes.

5. In a machine for packing cigarettes into a packet, a pusher for transferring cigarettes from one feed band to successive feed 25 bands and means on said pusher to increase the spread thereof during a portion of the pusher movement.

6. In a machine for packing cigarettes into a packet, a pusher for feeding cigarettes 30 to the packet, said pusher being formed with a lateral extension movable into and out of operative position and means for operating said pusher extension located adjacent the path of travel of said pusher.

40 7. In a machine for packing cigarettes into a packet, a pusher for feeding cigarettes to said packet from successively stepped feed bands, means on said pusher to increase the spread thereof during a portion of the pusher movement and means for automatically lowering said pusher to engage said cigarettes on said successively stepped feed bands.

8. In a machine for packing cigarettes 50 into a packet, a pusher adapted to feed group of cigarettes to said packet, a lateral extension on said pusher and means for moving said extension into and out of operative position during the operation of said pusher, 55 whereby layers comprised of different numbers of cigarettes may be engaged by said pusher.

9. In a device as per claim 8, in which said means for moving said extension includes 60 a roller carried by said extension, a cam bar disposed in the path of said roller and means for urging said roller against said cam bar.

65 In testimony whereof I affix my signature.
ROBERT WILHELM VOIGT.
